POLYMERIZATION OF OLEFINS

Jacque C. Morrell, Chicago, Ill., assignor to Universal Oil Products Company, Chicago, Ill., a corporation of Delaware

No Drawing. Application March 31, 1936,
Serial No. 71,959

18 Claims. (Cl. 196—10)

This invention relates to the treatment of hydrocarbons and more particularly refers to the treatment of olefinic hydrocarbons which are normally gaseous at ordinary temperature and pressure.

Olefinic hydrocarbons are generally more chemically active than other classes of hydrocarbons. Hydrocarbons containing a triple bond or more than one double bond between carbon atoms are particularly active. When unsaturated hydrocarbons are subjected to the influence of a polymerizing catalyst, they condense and form substances of higher molecular weight. The more active olefinic hydrocarbons are extremely sensitive to polymerization catalysts and form hydrocarbons of a higher molecular weight under relatively mild conditions of treatment.

Olefinic hydrocarbons with which the present invention is concerned occur along with corresponding paraffinic or saturated hydrocarbons in commercial hydrocarbon mixtures, such as those encountered in the cracking of petroleum, in gas-making processes and as by-products in various chemical industries. As a result of cracking, olefins are found in large percentages in the fixed gases as well as in the gasoline boiling range fractions. Normally these fixed gases from the cracking processes are utilized as fuel. Only a very small percentage of the gases produced by cracking are subjected to processes for the utilization of the olefinic constituents.

Alcohols such as isopropyl alcohol and others are produced commercially to some extent by first absorbing the olefins in the cracked gases in sulfuric acid and subsequently hydrolyzing the acid esters to produce the desired alcohols.

The present invention provides for more effectively utilizing the olefinic constituents of commercial hydrocarbon mixtures, particularly those occurring in the gases from oil cracking processes, to produce various derivatives therefrom. This process may also be applied to individual olefins or mixtures of olefins produced by special chemical methods, or by fractionation of mixtures of hydrocarbon gases.

In one specific embodiment the invention comprises treatment of normally gaseous olefins and hydrocarbons at elevated temperatures, to produce polymers therefrom, utilizable as constituents of motor fuel with the salts of persulfuric acid which are known as persulfates. In another specific embodiment pyrosulfuric acid may be used either alone or in admixture with the persulfates.

The present process is particularly directed to

the production of dimers and trimers from mono-olefins, particularly such olefins whose lower polymers boil at temperatures within the approximate range of commercial motor fuel, say for example, from 100 to 400° F. It has been found that the dimers and some of the trimers of propylene, the butylenes and amylenes boil within this range and furthermore that these compounds have unusually high antiknock characteristics. The following table shows the approximate boiling points of the dimers of propylene, butylenes, amylenes and hexylenes which will occur in appreciable quantities in the gases and the lower boiling liquids from oil cracking processes.

15

Boiling points of olefin dimers

Hexylene	155° F.
Octylene	255° F.
Decylene	323° F.
Dodecylene	417° F.

20

15

The lower boiling and normally gaseous olefins, particularly ethylene, are the more resistant to polymerization. By proper selection of the more active combination of catalysts and by treatment under more drastic conditions, it is found that these relatively inert lower boiling gaseous olefins may also be readily polymerized.

25

One of the essential ingredients of the catalysts which may be employed in catalyzing olefins according to the present invention, are the salts of persulfuric acid ($H_2S_2O_8$). The most easily formed persulfate is that of ammonia, which is conveniently prepared by the electrolysis of ammonium sulfate in compartment cells, the ammonium persulfate being continuously formed by anodic oxidation, and the anode solution being continuously replenished by the addition of ammonium sulfate. The persulfate is a white crystalline solid which has a specific gravity of 1.982. 40

30

Other persulfates, such as, for example, those of sodium or potassium, may be prepared by adding their carbonates or hydroxides to concentrated solutions of ammonium persulfate whereupon the persulfates of alkali metals precipitate. 45 These compounds may be employed advantageously in particular cases either alone or in combination with the ammonium salt. Persulfates of the following metals are also available: lithium, caesium, rubidium, calcium, magnesium, strontium, thallium, lead, manganese, iron, nickel.

35

Other catalysts which may be utilized in polymerizing olefins will have as their active constituents salts of pyrosulfuric acid of the formula $H_2S_2O_7$. This acid may be considered as a 55

compound of one molecule of water and two molecules of sulfur trioxide and as corresponding to a sulfuric acid containing 45% free sulfur trioxide by weight. It is a crystalline solid melting at 35° C. Numerous salts of this acid have been prepared, the most common of which are those of sodium and potassium, which are best prepared by the action of sulfur trioxide upon their anhydrous normal sulfates. Sodium pyrosulfate $\text{Na}_2\text{S}_2\text{O}_7$ has a melting point of 400° C., and a density of 2.66. The melting point of the potassium salt is slightly higher being 414° C., while its density is slightly lower; that is 2.51. In addition to the two simple salts mentioned, the existence of the following double salts has been confirmed:

25 A convenient method of operation consists in incorporating the salt to be used with spacing or absorbent material, such as fuller's earth or other relatively inert materials.

30 Catalysts may be prepared by adding water solutions of the salts of pyrosulfuric or persulfuric acids to a solid absorbent material such as kieselguhr; thoroughly mixing the ingredients and subjecting them to heat at a temperature of approximately 500° F. for the purpose of driving off the excess moisture. Small amounts of carbonizable material, such as starch or agar agar may be added prior to the mixing and heating.

35 Salts of the pyrosulfuric and persulfuric acids may also be added to the spacing agent in solid form and the constituents ground, mixed, and heated.

40 After heating the catalyst mixture, it is ground and sized. If desired, the catalyst may be shaped in specially desired forms and baked in that state.

45 A number of different absorbent carrying materials, which vary somewhat in their absorptive capacity, and also in their chemical and physical properties and their influence upon the catalytic effect of the mixture, may be employed. One class comprises materials of predominantly siliceous character and includes diatomaceous earth, kieselguhr and artificially prepared porous silica. Some of the naturally occurring diatoms 50 will contain minor amounts of highly active aluminum oxide which in some instances seems to contribute to the total catalytic effect of the solid catalyst.

55 Another class of materials which may be employed either alone or in conjunction with the first class comprises generally certain members of the class of aluminum silicates and includes such naturally occurring substances as various fuller's earths and clays, such as bentonite, montmorillonite, etc. The class also includes certain artificially prepared aluminum silicates of which a purified aluminum silicate made by treating certain selected clays with hydrochloric acids or 60 other mineral acids and washing out the reaction products is representative. The naturally occurring substances of this type are characterized by a high absorptive capacity and they may also contain traces of active ingredients which assist in producing the desired polymerizing effects.

Again each substance which may be used alternatively will exert its own specific influence, which will not necessarily be identical with that of the other members of the class.

5 In some cases the structure of the solid pyrosulfuric or persulfuric catalysts may be improved by the primary incorporation of minor quantities of organic materials which yield a carbonaceous residue on heating. Substances which may be used in this manner include such materials as cellulose, starches, sugars, glue, gelatin, flour, agar-agar, etc. They evidently function as binders to some extent to prevent the breakdown of the catalyst structure when subjected to elevated temperatures and the action of hydrocarbon gases. The catalyst composite may be used in particle sizes of from approximately 5 to 20 mesh or may be made up into small briquettes.

10 Owing to the possibility of varying the ingredients which go to form the catalyst masses, a number of alternatives exist, each of which will have its own peculiar catalyzing and polymerizing character, which will not be exactly equivalent to masses of different composition.

15 While treatment of olefinic gaseous hydrocarbons by persulfates and pyrosulfates may be effected in a variety of ways, a few of which will be mentioned as indicating the wide applicability of these compounds. A convenient method of 20 use consists in placing a mass of finely divided catalytic composite granules in a tower or column through which the vapors may pass upwardly or downwardly, preferably the latter. The melting points of the salts most commonly employed are 25 considerably above the temperature under which treatment is normally carried out in practice. It is within the scope of the invention to employ a number of treating towers in parallel so that olefinic gases may be continuously treated, a 30 tower containing fresh treating reagent being cut in as the others become spent.

35 The polymerizing of gaseous olefins with catalysts of the present character may be brought about under numerous combinations of temperature and pressure although the best results for any given pure olefin or mixture of olefins, such as those encountered in the gases from oil cracking plants, will usually correspond to a particular set of conditions. It is a feature of the present type of catalyst that treatment may be conducted at temperatures as high as 550° F. and superatmospheric pressures up to several hundred pounds per square inch without danger of 40 over-polymerization resulting in the formation 45 of heavy tar-like polymers instead of liquids of gasoline boiling range.

50 After the catalysts have been in operation for some length of time, they become fouled by carbon particles depositing on their surfaces. The 55 catalysts included in the present classes are readily regenerated after they have been contaminated by surface carbon deposits, merely by burning off the deposits with air or other oxidizing gas at moderate temperature. Following the combustion of the surface carbon, steam may be introduced to supply water of hydration which had been in part driven off during the regeneration operation.

55 The following results were obtained in polymerizing olefinic gases when using catalysts of the type comprised within the scope of the invention. Although a number of other examples are available, these are characteristic.

Example 1

A catalyst comprising 50% sodium pyrosulfate by weight and 50% by weight of kieselguhr was first thoroughly mixed and then heated to approximately 550° F. The solid mass was then ground to produce particles from 5 to 10 mesh size.

The catalyst was placed in a vertical treating tower as a filler. Gases from a stabilizing unit 10 having the following composition were passed downwardly through the treating tube, under a pressure of 125# per square inch and a temperature of approximately 375° F.

	Percent
15 CH ₄	0.5
C ₂ H ₄	0.7
C ₂ H ₆	5.6
C ₃ H ₆	11.9
20 C ₃ H ₈	27.8
1-C ₄ H ₁₀	16.4
1-C ₄ H ₈	7.9
n-C ₄ H ₈	13.2
n-C ₄ H ₁₀	16.0

25 This polymerization operation produced approximately five gallons of polymer product per thousand cu. ft. of gas mixture treated. From the following table giving the properties of this liquid polymer product it is obvious that a premium gasoline fuel is produced.

A. P. I. gravity	61.8
Gum A. S. T. M. mg/1000 cc	5
Octane number—motor method	81
35 Vapor pressure lbs./sq. in. Reid	9.0
I. B. P.	100° F.
50% over	206
95% over	372
End point	404

Example 2

In this example, potassium pyrosulfate

(K₂S₂O₇)

45 was added in equal parts by weight to kieselguhr and the mixture stirred and heated to approximately 550° F. The baked catalyst was then broken up and sized into small particles.

The catalyst then was subjected to contact with similar gas under the same conditions of temperature and pressure as given in Example 1.

50 As a result of contact with the catalytic material, a liquid polymer product of approximately 4.5 gallons per thousand cu. ft. of gas mixture treated was produced and had the following composition.

A. P. I. gravity	61.2
Gums A. S. T. M. mg/1000 cc	6
Octane number—motor method	82
60 Vapor pressure lbs./sq. in. Reid	8.5
I. B. P.	108° F.
50% over	212
95% over	385
End point	410

65 The foregoing disclosure of the nature of the invention and description of one of its operations will serve to define its scope and indicate to a large extent its value in the art to which it applies. However, since the process is applicable to treatment of any mixture of olefins by pyro and persulfuric acid salts, and since the apparatus used and the conditions of operation may be varied over a wide range, it is not intended that the foregoing descriptive matter and the

examples given be construed as limitations on the broad scope of the invention.

I claim as my invention:

1. A process for the conversion of normally gaseous olefins into liquid olefin polymers, which 5 comprises subjecting olefin-containing gas, at a temperature adequate to polymerize said olefins, to the action of a solid catalyst comprising a mixture of a salt of pyrosulfuric acid and a solid adsorbent.

10 2. A process for the conversion of normally gaseous olefins into liquid olefin polymers, which comprises subjecting olefin-containing gas, at a temperature adequate to polymerize said olefins, to the action of a solid catalyst comprising a salt 15 of pyrosulfuric acid.

3. A process for the conversion of normally gaseous olefins into liquid olefin polymers, which comprises subjecting olefin-containing gas, at a temperature adequate to polymerize said olefins, 20 to the action of a solid catalyst comprising a mixture of an alkali metal salt of pyrosulfuric acid and a solid adsorbent.

4. A process for the conversion of normally gaseous olefins into liquid olefin polymers, which 25 comprises subjecting olefin-containing gas, at a temperature adequate to polymerize said olefins, to the action of a solid catalyst comprising an alkali metal salt of pyrosulfuric acid.

5. A process for the conversion of normally 30 gaseous olefins into liquid olefin polymers, which comprises subjecting olefin-containing gas, at a temperature adequate to polymerize said olefins, to the action of a solid catalyst comprising a mixture of an alkaline earth metal salt of pyro- 35 sulfuric acid and a solid adsorbent.

6. A process for the conversion of normally gaseous olefins into liquid olefin polymers, which comprises subjecting olefin-containing gas, at a temperature adequate to polymerize said olefins, 40 to the action of a solid catalyst comprising an alkaline earth metal salt of pyrosulfuric acid.

7. A process for the conversion of normally gaseous olefins into liquid olefin polymers, which 45 comprises subjecting olefin-containing gas, at a temperature adequate to polymerize said olefins, to the action of a solid catalyst comprising a mixture of a heavy metal salt of pyrosulfuric acid and a solid adsorbent.

8. A process for the conversion of normally gas- 50 eous olefins into liquid olefin polymers, which comprises subjecting olefin-containing gas, at a temperature adequate to polymerize said olefins, to the action of a solid catalyst comprising a heavy metal salt of pyrosulfuric acid.

55 9. A process for the conversion of normally gaseous olefins into liquid olefin polymers, which comprises subjecting olefin-containing gas, at a temperature adequate to polymerize said olefins, to the action of a solid catalyst comprising a calcined mixture of a salt of pyrosulfuric acid and a solid adsorbent.

60 10. A process for the conversion of normally gaseous olefins into liquid olefin polymers, which 65 comprises subjecting olefin-containing gas, at a temperature adequate to polymerize said olefins, to the action of a solid catalyst comprising a calcined mixture of a salt of pyrosulfuric acid and kieselguhr.

70 11. A process for the conversion of normally gaseous olefins into liquid olefin polymers, which comprises subjecting olefin-containing gas, at a temperature adequate to polymerize said olefins, to the action of a solid catalyst comprising a 75

- calcined mixture of a salt of pyrosulfuric acid and a siliceous material.
12. A process for the conversion of normally gaseous olefins into liquid olefin polymers, which comprises subjecting olefin-containing gas, at a temperature adequate to polymerize said olefins, to the action of a solid catalyst comprising a calcined mixture of a salt of pyrosulfuric acid and a solid adsorbent and an organic material which yields a carbonaceous residue on heating. 5
- 10 13. A process for the conversion of normally gaseous olefins into liquid olefin polymers, which comprises subjecting olefin-containing gas, at a temperature adequate to polymerize said olefins, to the action of a solid catalyst comprising a mixture of a salt of pyrosulfuric acid and a solid adsorbent containing aluminum oxide. 15
- 20 14. A process for the conversion of normally gaseous olefins into liquid olefin polymers, which comprises subjecting olefin-containing gas, at a temperature adequate to polymerize said olefins, to the action of a solid catalyst comprising a calcined and briquetted mixture of a salt of pyrosulfuric acid and a solid adsorbent. 20
- 25 15. A process for the conversion of normally gaseous olefins into liquid olefin polymers, which comprises subjecting olefin-containing gas, at a temperature adequate to polymerize said olefins, to the action of a solid catalyst comprising a calcined mixture of salts of persulfuric and pyrosulfuric acids and a solid adsorbent. 25
- to the action of a solid catalyst comprising a mixture of salts of persulfuric and pyrosulfuric acids and a solid adsorbent. 10
16. A process for the conversion of normally gaseous olefins into liquid olefin polymers, which comprises subjecting olefin-containing gas at a temperature adequate to polymerize said olefins to the action of a solid catalyst comprising a calcined mixture of salts of persulfuric and pyrosulfuric acids and a solid adsorbent. 5
17. A process for the conversion of normally gaseous olefins into liquid olefin polymers, which comprises subjecting olefin-containing gas at a temperature adequate to polymerize said olefins to the action of a solid catalyst comprising a calcined mixture of salts of persulfuric and pyrosulfuric acids and kieselguhr. 15
18. A process for the conversion of normally gaseous olefins into liquid olefin polymers, which comprises subjecting olefin-containing gas at a temperature adequate to polymerize said olefins to the action of a solid catalyst comprising a calcined mixture of salts of persulfuric and pyrosulfuric acids and a solid adsorbent and organic material which yields a carbonaceous residue on heating. 20
